BEAM-TYPE HOUSING STRUCTURE

Earl J. W. Ragsdale, Norristown, and Albert G. Dean, Narberth, Pa., assignors to Edward G. Budd Manufacturing Company, Philadelphia, Pa., a corporation of Pennsylvania

Application April 14, 1934, Serial No. 720,650

23 Claims. (Cl. 105—399)

This invention relates to rail cars of the extremely light weight high speed type today being commonly used in the composition of articulated trains for high speed gas electric service. These 5 cars made of high tensile metal such as cold worked stainless steel or light weight aluminum, are being built in extremely light units only a minor fraction of the weight of standard rail-way cars for passenger and express service, are 10 being organized together by connection to common trucks intermediate the cars, are being streamlined, and highly powered by gas electric power plants carried by the cars themselves. The trains so organized are expected to continue 15 so organized over considerable periods of time and not to be shortened or lengthened through subtraction or addition of cars in daily use though such cars may be introduced from one period of the year to another by special operation in the yard or in the shop. Such trains afford a high speed, extremely economical, efficient, commodious and comfortable service of 20 considerable profit to the railroads.

While the invention has this general adaptation, it may, of course, have other adaptation but it is without doubt especially adapted for this field.

Its objects are to increase the reduction in weight of such trains without decreasing their 30 strength and safety, to actually increase their strength and safety while reducing the weight, to increase the facility of their fabrication, especially of high tensile stainless steel cold drawn and electrically spot welded, to improve the efficiency of the welding operations and the economy 35 thereof, to improve the appearance of the train, to render the construction of more ready streamlining and afford application of streamlined sheathing with greater facility and greater smoothness of curvilinear contour, to afford a 40 construction adaptable for general usage in connection with cars of different dimensions, and to facilitate the production methods employed.

Yet further objects are the arrangements for 45 transversely and longitudinally strengthening the sub-flooring structure of the car to enable it to constitute more efficiently the bottom chord member of the truss involving the car at large, to encompass in its transverse cross sections 50 spaces within which many of the car appliances may be contained and to provide for the enclosure of these equipment spaces and the sub-floor framings by streamline sheathings which, while affording resistance form to the exterior, 55 nevertheless, provide free access to the spaces

for installation, repair and replacement of equipment.

Still further, the invention has to do with the improvement in those flooring and side wall structures intersected by ways of ingress and egress to the car in such manner as to preclude 6 weakening of the structure where such intersections occur.

That which is looked upon as the best embodiment of the invention at the present time is 10 shown in the accompanying drawings of which—

Figure 1 is a side elevation of a rail car of such a train, in this instance the rearmost car of 15 streamline form being shown in connection with the rear or right hand end.

Figure 2 is a plan view of the same with half of the roof section broken away to show the side wall in horizontal section and the seats in plan.

Figure 3 is a side elevation of the framework 20 of the car showing particularly the side trussing and the vertically extending members of the transverse frames which are incorporated in this trussing.

Figure 4 is an enlargement of the left hand 25 end of the framework of Fig. 3 adjoining the left hand end of the car.

Figure 5 is a partial such enlargement of the opposite side of this left hand end.

Figure 6 is an enlarged view of one half of the 30 left end elevation of the framework of Fig. 3, the half shown being that adjoining the side the portion of which is shown in Fig. 5, and which is the side opposite that shown in Fig. 3.

Figure 7 is a section on lines 7—7 of Figs. 5 and 6 looking in the direction of the arrows.

Figure 8 is a section on line 8—8 of Fig. 6 looking 35 in the direction of the arrows.

Figure 9 is one half of a full transverse cross section of a car of Figs. 1 to 3.

Figure 10 is a plan view of the bottom portion 40 of a transverse frame unit of Fig. 9 taken approximately on line 10—10 of Fig. 9 and with certain members broken away and foreshortened in order to compact the view.

Figure 11 is a section approximately on line 45 11—11 of Fig. 9 in the direction of the arrows.

Figures 12 to 28 inclusive are cross sectional details of the various members of the framework of Figs. 3 to 6 taken each upon the cross sectional lines designated in Figs. 3 to 6 by the numerals 50 corresponding to the number of the figure, applied to opposite ends of the cross sectional lines, and looking in the direction of the applied arrows, in accordance with the customary practice.

Figure 29 is an over-all plan view of the under- 55

frame structure in the vicinity of the side doors of the car taken substantially from the same point of view as the partial section of Fig. 10 on line 10-10.

Figure 30 is a partial side elevation of one of the vertical trusses entering into this under-frame structure taken on line 30-30 of Fig. 9 and Fig. 29.

Figure 31 is an enlarged transverse section substantially on line 31-31 of Fig. 29 showing in enlarged scale certain of the features appearing at the floor level in Fig. 9 with particular relation to the underframe structure of Fig. 29.

The car depicted in side and end elevations and plan in Figs. 1 to 6 is the endmost car of a multiple car train. Its forward or left hand end designated 40 is substantially square ended and thereby adapted to adjoin the square ended rear end of the car in front through connection with a common truck the rear half of which is represented by the rear wheel 41 of the truck. The truck and the articulated connection of the trains thereto form no part of the present invention and is therefore not shown to any additional extent. The rear end of this car designated 42 is curvilinearly tapered as appears especially in the plan of Fig. 2 and thereby streamlined appropriately as the trailing end or tail of a streamline body. In the instance of the front or head car of the train it is the forward end (which in this case would be the left hand end of the car) which would be streamlined to curvilinear contour and in the instance of the forward end the contour would be appropriate for the leading end of the streamline body. This rear end 42 is supported by a truck individual to it represented as a four wheel truck through the showing in the elevation of Fig. 1 of two wheels 43.

The skeleton framework of the car depicted at large in Figs. 3 to 6 and 9 is of such longitudinal and transverse cross section as to afford a curvilinearly streamline form to the body of the car both transversely and longitudinally as appears particularly well in Fig. 9 from the transverse aspect and in Figs. 1 and 2 in the longitudinal aspect. This framework is covered by sheathing in the main longitudinally extending. The truss work of the side frames shown in Fig. 3 is sheathed below the belt line 44 at the level of the window sills with a relatively wide concavely cross sectioned longitudinally extending paneling 45 shown in cross section in Fig. 9. This paneling extends all the way down to the floor level 46. Below the floor 46, the under-framing is longitudinally sheathed by corrugated paneling 47, the corrugations of which are less in width than the concave elements of the paneling 45. Between the windows 48 the trusswork is sheathed by flat or finely longitudinally corrugated panelings 49. The roof above the top rails 50 finds the tops of the transverse frames of Fig. 9 sheathed throughout the roof quarter by longitudinally extending and longitudinally corrugated paneling 51 very similar to the paneling 47 utilized to sheath the bottoms. The central portion of the top beyond the roof quarter is sheathed as shown by longitudinally extending corrugated paneling 52.

These panelings each through their longitudinally extending concavities or corrugations as the case may be, and through and by virtue of their frequent strong welded connection with the members of the framework of Figs. 3 to 6 and 9, especially with the vertically extending members of that framework, greatly increase the

stiffness and strength of the side trusses at large as appearing in Fig. 3 and greatly increase the stiffness under compression strains of the roof members especially in the quarter sections of the roof covered by the longitudinally extended panelings 51. The side panelings 45 are provided each concave section with complementary inward turned flanges 53 themselves electrically spot welded together and with angle brackets 54 spot welded the one branch to the flanges 53 and the other branch to the vertical members 55 of the side frame trussing and of the transverse frame units. They may also be connected through such angle brackets 54 with certain of the diagonal members, e. g., 56-67. So organized the concave cross section and the angle walled flanges afford a great stiffness and strength. Similarly the panelings 47-49-51 are joined at the bottoms 58 of the corrugations by electrical spot welding likewise to the vertically extending members 55 of the side frames and the transverse frame units of Fig. 9. These frame members 55 are in the main of channel cross section presenting outwardly as appears clearly in Figs. 4 and 10 and are provided with outward turned flanges 59 to which these spot welded joiners are made either directly as in the case of joining the bottoms of the corrugations 58 of panelings 47-49-51 or indirectly as in the instance of joiner of paneling 45 through brackets 54. The mouths of the channels 55 may or may not be covered by cover plates 60 spot welded to these same flanges in which event the joiner of the paneling is by spot welding to flanges 59 through the cover plate thickness.

In the forward end of the car, the left end, these panelings terminate abruptly in a relatively sharp corner (see Figs. 2 and 7). In the rear end they are extended in flowing curvilinear lines of convergent form to a smoothly curvilinear extreme rear end. This rear end contour is characterized by a continuation of the floor line 46, the belt line 44, and the top rail 50 in parallelly extending horizontal planes all the way to the rear end and by the arrangement of the vertically extending members 55 of the side frames all truly vertical and parallel in those portions lying between the floor plane 46 and the top rail plane 50. Indeed, as clearly appears from Fig. 9, the truly vertical portions of the members 55 are extended somewhat beyond both the top rail plane 50 and the floor line 46 whereby all paneling between the planes 46 and 50 partakes of simple rather than compound curvature and the formation of the paneling to streamline form is facilitated. Similarly the transverse curvature of the panelings 47 and 51 is maintained of the same degree almost to the rear extremity of the car, only two frameworks removed therefrom as clearly appears in Figs. 1 and 3, that is to say, to the point 61, whereby the compound curvature rearwardly to this point 61 is not complex, and the form of the transverse frame units depicted in Fig. 9 is not changed except as to width. Thus there is left only the relatively small roof and bottom sections lying between the point 60 and the rear extremity where the compound curvature of the sheathing is complex. These relatively small areas designated 62 may then be hammered or die formed to shape.

The basis of the skeleton framework depicted at large in Figs. 3 to 6 and 9 and in detail in the remaining figures is the transverse frame unit of Fig. 9, details of which are shown in Figs. 10 and 11. This unit embodies not only the ver-

tically extending posts 55 but the transversely extending and curvilinear top and bottom members 63 and 64. In fact the panelings 47 and 51 are secured in large part to the curvilinearly extending lateral extremities of these top and bottom members 63 and 64. These members like the posts 55 are of channel cross section presenting outwardly of the framework and having outturned side flanges 65. The cross sections correspond in general to the dimension of the cross section of the posts 55 and lap these cross sections just above the top rail 50 in the one case and just below the floor line 46 in the other case. At these points of lap the side walls are spot welded together through side wall gussets 66 and 67 of appropriate extent and cross section. To facilitate fabrication the extremely curvilinear portions on the roof and bottom quarters in the region of the panelings 47-51, they may be fabricated separately from the central less curvilinearly formed portions and lap joined thereto by spot welding as indicated at 68. All of these channel cross sections may be closed across their mouths in the same manner as the channel cross section of the posts 55 as shown in Fig. 10.

While the top or roof section of the frame units 9 is simple in form as illustrated, consisting principally of the curvilinearly transversely extending portion 63, the bottom is compound in form, the bottommost member 64 being combined with the transverse horizontally extending floor beam 69 through intervened diagonal and vertical struts 70-71-72 to constitute a deep bottom truss, the outlines of which encompass considerable of the space below the floor beams 69. In the achievement of this the floor beams 69, themselves of upwardly presenting channel cross section as appearing in Figs. 10 and 11 and continuous from side to side of the frame unit, are joined at their opposite ends through gussets 67 which exteriorly overlap their side walls directly to the side walls of posts 55 and bottom frame members 64. Outturned flanges on the gussets 67 bear upon outturned flanges on the floor beams 69 and are spot welded thereto. These same gussets 67 receive the upper ends of the channel sectioned diagonal struts 70 which are secured thereto by welding while the lower ends of struts 70 are received by and secured by external gussets 73 commonly exteriorlylapping the side walls of the member 64 and welded thereto. A compound diagonal strut of hollow cross section 71 interconnects by its opposite ends gussets 73 and gussets 74 of elongated extent welded to the floor beam 69 intermediate its middle and its end. Pairs of vertical struts 72 spaced somewhat apart are welded exteriorly of gussets 74 by the bottoms of the channel cross section and at their lower ends through similar connection to spaced gussets 75 to the side walls of the bottom member 64. As a matter of fact there are four of these vertical struts 72 in this plane, one pair 72 on each side of the floor beam 69 and member 64 as clearly appears from a plan view of Fig. 10. So organized as will be clearly apparent, the struts 70-71-72 triangularly interconnect the members 64 and 69 after the fashion of a Warren truss and afford the relatively deep truss a great strength.

There are a large number of these transversely extending frame units in the skeleton framework of Fig. 3, there being located one flanking each window opening 48 and each door opening 76 and at each extremity of the car body. Intermediate the sides of the window openings there are inter-

mediate such transverse frame units as indicated, essentially similar to the principal such units, differing therefrom principally in the breaking of the posts 55 at the window openings 48. They are interconnected not only by the longitudinally extending sheathing 45-47-49-51 previously described but also by longitudinally and diagonally extending framing now to be described.

The vertically extending posts 55 of the frame are interconnected at their bottoms by bottom rails 77 of compound cross section appearing in Fig. 9 near the floor level 46 and the transverse cross section of which taken on line 22-22 of Figs. 3 and 4 is depicted in Fig. 22. These bottom rails are comprised of three similarly cross sectioned longitudinally extending channel members 78 each presenting toward the post 55 and provided with outturned flanges 79 through which they are spot welded to the flanges 59 and the bottom wall 80 of the post. There are two of these opposite each other just at the floor level and one just below at the bottom end of the post 55 and on the outside of it. Spaced between the upper and lower channels 78 there is secured a section of longitudinally corrugated sheathing 81 the edges of which are spot welded to the flanges 79 and therethrough to flanges 59 of the post. Below the lower channel 78 there is provided a longitudinally extending stringer 82 of Z cross section one arm of which is welded to flange 79 of the channel the main body of which underlies the main body of the post 55 and the other arm of which is welded to the sheathing 47 and member 64. The flanges 79 of the upper and juxtaposed channels 78 are joined together by channels 83 the side walls of which are welded to flanges 79. These channels extend from one post 55 to the next adjoining thereby constituting the juxtaposed channels 78 a full box cross section as clearly appears in Fig. 22. The exterior and interior paneling or gusseting or bracketing as may be desired will be provided with a longitudinally extending side edge 84 lap welded to intermediate flanges 79 and side walls of channels 83 by multiple welds. The structure is extended longitudinally of the car from end to end, the members 78 being continuous and the members 83 broken only by the posts 55 but reinforced at these points by the intermediate laps 84 of material which bridge across the post 55 and longitudinally reinforce the structure at those points where channels 83 are discontinuous. Such members 84 are also provided in connection with the lower channel 78 and have the same purpose of reinforcement, thus there is constituted a longitudinally extending girder of great stiffness and strength and at the same time through the prominence given the channels 78 and the contours thereof and of the paneling 81 affording ornamental moulding characteristics of an attractive order. The members 84 also serve as spacers between channels 83 and flanges 79 which will admit free use of gussets at the points of juncture of the various truss elements without disturbing the rectilinear course of the channel 78 and flanges 79. At these points of juncture the members 84 are terminated and the gussets supplant them.

At the belt line 44 there is located a longitudinally extending belt rail designated generally 70 in Fig. 9 by the numeral 85. This belt rail also constitutes the window sills, the section of the rail at various points designated respectively 21-21 and 24-24 in Fig. 3, is shown in Figs. 21 and 24. Fig. 21 shows the section intermediate the

windows 48 while Fig. 24 shows the section in the windows 48 transversely of the window sill. As in the instance of the bottom rail 11, the rail is composite. In this case it is formed of outer 5 longitudinally extending sheet metal channels 86 and inner longitudinally extending channels 87 of somewhat shallower depth than those channels 86. The side walls of both channels carry laterally extending flanges 88 through which they are welded to the post 55 and to the sections 10 of the paneling 45 and 49 appearing in Figs. 1 and 9. As in the instance of the bottom rail 11 just described, between the flanges 88 of channels 86-87 and the flanges 59 of the posts there 15 are intervened members 84 which are the gussets at the posts 55 and spacers intermediate the posts which admit the gussets without diverting the rectilinear course of the channels 86. In certain instances the members 84 may be flanges 20 on the paneling, but outstandingly, they are the gussets or spacers. In between the windows as shown by the section 21 the channels 86 and 87 are joined together by transversely arranged channels 83 of the same order as those 83 bearing 25 the connection with the bottom rail 11 of Fig. 22 and in the same manner are joined the side walls of 83 to the flanges 88. The channels 83 are of the same extent, extending from one post 55 to the next adjoining. Thus, as clearly 30 appears in Fig. 21, the section of the belt rail is a box cross section between the posts. Within the windows, as appears in Fig. 24, channels 83 are provided at the bottom of the cross section only. At the top the inner channel 87 has its 35 upper side wall extended all the way across to the outer channel 86 and there provided with a flange 89 mating with and welded to the flange 88 of the other channel. This provides an uninterrupted upper wall 90 to constitute the face 40 of the window sill proper and to admit the placement of windows from the inside of the car to lie against flanges 88 and 89 which are disposed at the outside. To facilitate this the upper angle of channel 87 adjoining wall 90 is formed with a 45 bevel 91, or perhaps its equivalent, a rounded corner. In the interest of added strength the members 84 are carried all the way through the window sill, the outer one in the usual manner of the gussets at the post, the inner one at the 50 bottom in the usual manner but at its upper edge by providing it with an outturned flange 92 and spot welding this flange to the face 90 of the window sill.

Above the windows 48 the top rail designated 55 generally 58 in Figs. 1 to 6 and 9 is also constituted of box section composed of a quadrangular arrangement of channel cross sections similar to those employed in connection with the bottom rail 11 and the belt rail 85. This appears 60 from the sections of Figs. 12, 13, 14, 28 and 23 taken respectively on the lines of corresponding number in Figs. 3 and 4. Sections 12 and 14 are taken without the windows 48 and between adjacent posts 55. The compound structure in 65 such case is composed similarly in all essential respects to the compound structure of the belt rail 85 as can be seen by comparing Figs. 12 and 14 with Fig. 21, and also similarly to the upper part of the bottom rail 11. Thus there are used 70 inner and outer vertically disposed channels 93 and upper and lower horizontally disposed channels 83 the former being longitudinally continuous across posts 55 and the latter extending between posts only. The flanges 94 of the inner 75 and outer channels 93 are joined to the side walls

of the channels 83 through the intervened members 84 of the same order as those used in the belt and bottom rails. These top rails 50 differ in these sections principally by being vertically shallow. However, the section 14-14 is 5 marked by the interposition of a longitudinally continuous vertically extending web member 95 between the side walls of channels 83 and flanges 94 of channels 93 which member, as clearly appears from Fig. 14 and Fig. 1, is extended vertically above the box cross section of the top rail 50 a considerable distance, and is extended longitudinally over a considerable length of the car body. This member 95 is of considerable thickness and is so placed for the purpose of 10 stiffening and strengthening the top rail throughout the region in which it is used as will more fully appear. This it does by sub-dividing and stiffening the main box section and by entering into angular formation with the top walls of the 15 box section, deepening and increasing the effective area of the section at large.

Within the windows 50 and within the doorway 16 the sections 13, 28 and 23 are taken. Here the box cross sections are constituted of three 20 channel members only, the outer 93, the inner 93, and the upper of the channels 83, and the section is completed at the bottom by extending the lower side wall of the inner channels 93 outwardly to meet the lower side wall 96 outwardly 25 and there providing it with a flange 97, this construction being similar to that utilized at the window sills shown in Fig. 24. Here too members 84 are utilized in essentially the same manner as at the window sills, the inner of these 30 members being provided with a flange 92 as in the instance of the sill of Fig. 24. In addition, however, to the members 84 there is utilized the member 95 in a main body continuation, the same member appearing in the section of Fig. 14 35 and which extends all the way across the center 40 part of the car and across the side door 16. The flanges 94-97 and the members 84 and 95 are through welded from face to face of their multiple laps. At the door 16 the section of Fig. 23 45 is taken. Here member 95 also appears in the same relation to the other elements of the top rail as in the section 28-28 in the window opening. But at this section 23 in the door opening the extension of the inner channel 93 to meet the outer channel 93 is not by integral extension of 50 the bottom wall but by non-integral such extension, the extension being made by means of a channel 83 which has been obverted from the position of the bottom channel 83 usually occupied 55 to present upwardly as in case of the upper channel 83. However, the joinder is likewise by means of welding the side walls of the channel to the bottom flanges 84 of the channels 93. Thus there is formed a rabbeted upper door 60 jamb the rabbet lying inwardly between the lower side wall of the inner channel 93 and the flange 94 and the main body of the jamb being constituted by the bottom of the channel 83. To the bottom of this channel is welded by its side 65 wall a weather and stop channel 98. Such are the various bottom, belt and top rail structures.

The transverse frames of Fig. 9 and the rail structures just described are vertically inter-braced by the posts 55 of the transverse frames 70 and diagonally inter-braced by the system of diagonal braces appearing particularly in Figs. 3 to 6. The rigidity of the bracing of the posts 55 with the transverse frames is varied from point to point in accordance with the stress needed to 75

be met by varying the reinforcements of the post 55 as clearly appears in Figs. 15, 16 and 17 taken on lines of corresponding number in Figs. 3 and 6. Thus the post 55 of section 15—15 is reinforced by a channel 99 nested within it intermediate the top and bottom of the channel of the post and secured thereto by inter-welding of the side walls. Thus the base of the section 16—16 is reinforced by strips of material 100 welded both to the bottom of the channel of post 55 and to the cover plate 60 of this channel. Thus the post of section 17 is unprovided with reinforcements. Thus the door post of section 25—25 at the right of the doorways 76 is reinforced and enlarged by providing cover plate 60 with an extension 100 into the doorway and then providing it with an inturned flange 101. This extension is welded by the flange 102 to a Z shaped vertically extending member 103 the dimensions of the main body and the outer arm of which are such as to form with the adjoining side wall of the post 55 an augmenting box section greatly enlarging the cross-sectional area of the member as a whole. The inner arm 104 of this Z section member 103 extends inwardly of the body to form the rabbet complementary to that formed by channel 93 and flange 94 at the top of the door as shown in Fig. 23, while the outer arm of the Z together with flanges 102 and 101 form a weather and stop channel similar to the channel 98 and in the same door plane. The terminal portions 105 of the various inner and outer sheathings assist in strengthening this structure.

The diagonal braces are shown particularly by the sections of Figs. 18 to 20, 26 and 27 and are various in accordance with the various stresses required to be met. Thus the member of the section 18—18 is a box cross section comprised of oppositely facing channels 106 bound together by flat sections 107 welded to their side walls, thus the member of the section of Fig. 19 is comprised of a single channel member 106 and opposed flat members 107 welded to the side walls, and thus, the member of the section 20—20 is comprised of three channels 106 and opposed flat members 107 welded to each side wall. These relatively heavy and strong cross sections are used intermediate the trucks where the stresses are extremely heavy, but in the over-hang at the trailing end 42 the sections 26—26, 27—27 are used, a simple channel 106 or two channels 106 welded bottom to bottom. It is characteristic of all of these diagonal sections however that the channels 106 are of corresponding width and that this width accords with that of the channels 83 entering into the composition of the rail structures and that the gauge of the flat side members 107 corresponds to the gauge of the members 84 whereby the longitudinally continuous channels 78, 86, 87 and 93 may be extended without diversion of the rectilinear course across gussets and walls 107 alike, since the outer surfaces of the gussets lie in one and the same plane. The same is true of the paneling attachments whereby the paneling 65 may extend rectilinearly smoothly without diversion of the course. What is said of the rectilinear members is true also of the curvilinear members.

The relative arrangement in and about the side doors of the car of the various parts of the structure heretofore described is of considerable consequence. The invention at this point brings about the important results of enabling the side doors and communicating step wells to be freely used even in the most highly stressed parts of the structure without weakening it and without

putting it to undue torsional strains or resulting in undue deflection in any direction. The doors 76 extend from the longitudinally continuous top rail right through the belt rail 85 and the bottom rail 76 rendering these rails longitudinally discontinuous in the doorway. This would ordinarily so weaken the structure of such light weight as this drawn and pressed metal structure having the structural characteristics of an airplane as to preclude its use. It would require that the structure depend almost entirely for longitudinal strength and stiffness upon disjointed roof stringers 108 (see Fig. 9) (which stringers discontinuously extend from one frame member 63 to the next adjoining and are intended mainly to support the head linings of the car,) upon the longitudinally extending floor stringers 109 (again see Fig. 9) which support the corrugated car flooring 110, and upon the main longitudinal stringers or beams 111—112 which latter are located between the struts 72. There are four of these latter, the two bottommost of heavy cross section being longitudinally continuous and provided with flanges welded both to the vertical struts 72 and to the bottom of the channel section of the bottom members 64 of the transverse frame units of Fig. 9, and two of them, the uppermost being of open channel form similar to the floor stringers 90 welded by the bottom wall to the flanges of the floor beam 69 and by their side walls to the side walls of the channel section struts 72. These members 111—112 are the principal mid-section longitudinally extending tension members of the car. The floor stringers 109 are also tension members. Their bottoms are welded to the flanges 113 of the floor beams 69 (see Fig. 10 which will also show the relation of the stringer 111 to this beam). On these are supported in turn by flanges 114 the corrugations (now refer to Fig. 9) of the flooring 110, the bottoms of the corrugations being welded to the flanges 113 and the corrugations extending transversely of the car. Note in connection with the stringer 111 that to permit the struts 72 to come all the way up and be welded by their side walls to this stringer, flanges 113 are cut away and are supplanted intermediate the side walls of the beams 69 by the welded channel reinforcement 115 through which the beam is reinforced where the flanges are cut away. The over-head stringers 108 are lap joined to each other and to the bottom walls of the channels of members 63 by joining members 116 of flattish section welded to the respective bottom walls of the members 63 and 108. However, it must be apparent that all of these members together are of relatively small strength and resistance to torsion strain and general deflection as compared with the deep and strong side trusses which have been broken by the door 76.

Therefore in further accord with the invention the number of transverse frame units of Fig. 9 in the vicinity of the doors 76 is greatly increased throughout the range designated in Fig. 3, 117, the transverse frames being almost if not quite doubled in number on either side of the doorway and in the roof above the doorway being practically trebled in number. This is readily traced by counting the vertically extending members 55 and 63—64. Flanking each doorway the transverse frames are reinforced by transversely extending bulkheads 118 appropriately transversely stiffened and strengthened. These appear in Fig. 2 in plan and in Fig. 9 in elevation. These may extend from the roof down to the floor beams 69 75

or they may be extended all the way to the bottom member 64 of the transverse frame member. Header units 118A complete the bulkheads over the center doorways 16a. In addition, the bottom trusses of the transverse units of Fig. 9 as shown in Figs. 29 and 30 are supplementally interconnected together by an auxiliary system of stringers or beams 119-120 appearing especially in Figs. 9, 29 and 30. These stringers 119-120 are 5 in general of the same order as those 111 and 112 and we contemplate that in some installations at least they may be consolidated with them at an appropriate location intermediate the middle and the side of the transverse frame member. These 10 auxiliary stringers or beams extend throughout 15 the range 117. They are longitudinally trussed together from transverse frame unit to transverse frame unit as appears in Figs. 3 and 30 by diagonal struts 121. They are bound laterally 20 alike to stringers 111, floor beams 69 and floor 25 stringers 109 by floor gusset plates 122, 123 and 124 welded to the upwardly disposed flanges of these elements or to the bottom walls thereof as the case may be. As indicated clearly in the 30 plan of Fig. 29, these gussets are secured principally to the flanges of the floor beams 69 but are provided with upturned flanges 125, 126 the latter of which is laterally adjustable for placement fitting for welding to the side walls of the floor 35 stringers 109, the flange 126 being welded to the bodies of the members 122-123 and 124 after welding the side walls to allow for discrepancies in fitting. The gusset plate 124 is of substantially 40 the full extent of the range 117 about the doorway and perhaps greater but progressively these 45 plates 124-123-122 decrease in length in the order named until the central plate 122 is of a length only one or two transverse frames beyond the width of the doorway. Thus both transverse 50 and longitudinally extending beams and stringers at the floor level 46 are trussed together by this crotched system of gussets in such manner that all strains including the tension of the chord members intercepted by the step walls are taken 55 by the group as a unit and distributed gradually from the mid-section 127 between the stepped wells 128 out into the main side trusses of the structure.

The corrugated sheathings 51 and 52 of the 60 roof and 58 of the bottom interconnect top and bottom members 63 and 64 of these closely adjoining transverse frames in the range 117. Particularly in the roof are these corrugated sheathings converted into box sectioned inter- 65 connecting struts of short stubby form especially in and above the doorway 16, by the employment of an intermediate sheathing 129 (see Fig. 9). This may also be employed in the bottom of the structure.

The inter-action of these constructions becomes then as follows according to the best available knowledge. The short stubby box sections of the roof paneling closely spot welded to the members 63 constitute the section of the roof in 70 the range 117 and particularly above the doorway 16 extremely stiff and strongly resistant to longitudinal bending or torsional weaving, the more especially because this construction is carried down through the roof quarters sheathing 51 to the top rail 50 which is, of course, continuous. The top rail 50 reinforced as it is by the member 85 gives the lower edge of the roof in the range 117 an extreme stiffness. Backed by the bulkheads 118 flanking the doorway 16 and because 90 of the re-doubly closely positioned members 63

above the doorway, it becomes practically impossible to consequentially deflect this roof section in compression, bending or torsion strains. Lateral flexure of the door posts 130 is likewise resisted by the bulkheads 118 as anchored in the stiffened 5 and strengthened roof above the doorway. With or without the bulkheads 118 torsional bending or weaving is inhibited at the bottom by the through running truss stringers 119-120 and their diagonal bracing 121. Indeed the construction is such that the trusses 119-120 joined together as they are by the gussets 122-123 constitute a downwardly presenting channel section of the full depth of the bottom of the transverse frame. This can be discerned especially from 15 Fig. 9 where the channel can be defined as extending from one side wall of stringer 119 to stringer 120, the members 122-123 transversely and longitudinally reinforced by beams 69 and stringers 109, and the other side wall of the truss 20 extending from stringer 119 down again to the stringer 120 and the other side wall (not shown). Thus this section 119-120 between the step wells becomes substantially unbendable and such strains as those to which it may be subjected are 25 carried horizontally laterally outwardly and gradually distributed into the side trusses. Indeed the main loads of the side trusses are carried through the structure of Figs. 29 and 30 laterally inwardly to this extremely strong step 30 well section and then laterally outwardly again to the extension of the side trusses on the opposite side of the doorway. Withal the transversely and laterally stiff bulkheads 118 stay the 35 longitudinally extending members against any 40 dissymmetry of movement with respect to the medial transverse plane of the doorway as well as effect the inter-tying of the door and step well section for mutual resistance to torsional and 45 weaving strains. The transverse inner truss 46 webbing 122-123-124 from another standpoint becomes a principal longitudinal tension element 50 since the tensions of the lower chord members of the trusses are transmitted through the floor beams and connecting elements directly into it 55 and across the step well. From another angle this webbing 122-123-124 constitutes an X-shaped bracing, that is to say, a double diagonal bracing between the opposite side trusses across 60 the step well. The webbing is shown in Fig. 9 55 as well as in Figs. 29 and 30 but in Fig. 9 the detail is not attempted. It is illustrated as a webbing passing continuously beneath the floor 65 stringers 109 to above the floor beams 69. The detail of the webbing, of course, and its connection to the transverse and longitudinally extending structural element may be widely varied, the essential thing being that it is intimately tied to these elements and so formed as to be substantially 70 free of transverse extensibility. Its longitudinal continuity in its several portions, of course, makes it inextensible in the longitudinal direction.

Such is the nature of the invention. That its objects are achieved in full would seem to be 75 clear without repetition of the preamble of the specification. Suffice it to say that in addition to the great strength of the structure, particularly in the range where the truss chords are intersected by the doorways, that the organization for 80 assembly into unit transverse frames such as Fig. 9 of closed cross section and the building of these frames directly into the trusses admits a 85 rapid and efficient assembly. The transverse frames are set up in jigs at the proper dis- 90

tances apart, the gussets of their juncture with the longitudinal chord members or welded in place, and their alignment and spacing immediately assured by welding on of the inner and outer flanged channels the chord members. Thereupon completion of these chord members through the introduction of their intermediate channels and of the diagonal bracing follows rapidly. Throughout these and all other operations the structures afford a very maximum of accessibility for spot welding of the parts together through their meeting flanges and laps.

Suffice it to say further that the organization of the channel section posts of the transverse frame with the rails and the diagonal braces on the basis of the depth of the cover post structures 55 as the thickness dimension of the various intermediate channels and connecting diagonals enables the gusseted connection of the various truss elements to be effected by spot welding, and one to attain the placement of all exterior faces of the truss in a common plane or common curvilinear surface free from linear irregularities whereby the continuous longitudinal members 25 and the panelings may be welded in place without deflection from those planes or surfaces.

Suffice it to say once again that the utilization of the juxtaposed flanged channels on edge connected respectively with the inside and the outside of the posts 55 enables them to be constituted mouldings and sills at the same time that they constitute the through running continuous chord elements of the truss.

The effect of the whole is an immense saving 35 in weight coupled with an immense gain in strength.

In conclusion the following items of additional detail are perhaps worth noting. First, that the upper chord 119 of the truss 119-120 is rather 40 deep as shown in Figs. 9 and 30 and its side walls are transsected by the through beam 69, being cut away for this purpose as clearly appears in both Figs. 9 and 30. Second, that the continuity between members 122-123-124 is effectively 45 preserved by actual transverse overlap of the several plates the margins of which may be cut away at points like 129 to pass vertical struts such as 72. The same might be done in the plane of the truss 119-120 where the depth of 50 the chord member 119 is sufficiently shallow to permit it.

Note the front corners of the car as shown particularly in Figs. 5 and 6 and the detail of Figs. 7 and 8. Posts 55 around the corner from 55 each other are angularly inter-connected inside and out by angular brackets 130-131 and also by angular gussets of corresponding numerical designation in such manner that these brackets and gussets form a third corner box cross section 60 132 of large area intermediate the posts 55. The gussets afford the usual connection to the longitudinal and diagonal members of the truss, both the side truss and end truss appearing in Fig. 6, while gussets and brackets together are 65 so closely adjoined vertically of the structure as to constitute it vertically substantially of continuous boxed cross section from top to bottom.

In response to a requirement of division, claims 70 to the truss structure in general have been transferred from this application to copending divisional application Serial No. 193,870, filed March 4, 1938.

There are many aspects of the invention which 75 point the way clearly to modification and improvement. Such modification and improvement

may doubtless be made of all features of the invention. The circumstantial terminology of the appended claims should be held to apply to each and all such modifications in order that the generic spirit of the invention be upheld by them. Obviously our invention is applicable to trussed housing structures at large, particularly vehicle bodies at large, in all its features. The preambles to the claims especially, therefore, are intended to have that breadth of construction which will 10 comprehend such breadth of applicability.

What is claimed is—

1. A beam type vehicle body having side trusses and deriving its strength principally through said side trusses but having a doorway intersecting a chord of one of said trusses, body reinforcements to transmit the loads from the section of said truss on one side of the doorway to the section thereof on the other side through portions of the body inwardly removed from said truss comprising beams in the structure of the body inwardly removed from said trusses, transverse members relatively widely spaced interconnecting said trusses in locations remote from the doorway and transverse members in greater number per unit 20 of length interconnecting the side trusses and said beams in the region of the doorway.

2. A beam type vehicle body having side trusses and deriving its strength principally through said side trusses but having a doorway opening intersecting the lower chord of one of said trusses, body reinforcements to transmit the loads between the interrupted sections of said truss on the respective sides of the doorway through portions of the body inwardly removed from the side trusses, comprising longitudinally extending truss members located inwardly of said side trusses and means to interconnect said inwardly located truss members with said side trusses including transverse members extending substantially throughout the vertical height of the body and gussets spanning the distance between the side trusses and interconnecting them with said longitudinal and transverse members on each side of said doorway.

3. A beam type vehicle body having side trusses and deriving its strength principally through said side trusses but having a doorway intersecting a chord of one of said trusses, body reinforcements to transmit the loads from the section of said truss on one side of the doorway to the section thereof on the other side through portions of the body inwardly removed from said side trusses comprising longitudinally extending members located inwardly of said side trusses and transversely extending members interconnecting said side trusses and members together with gussets spanning the distance between the side trusses and interconnecting them with said longitudinal and transverse members on each side of 55 said doorway, said gussets having their minimum longitudinal dimensions in the median plane of the body and their maximum longitudinal dimension in their region of joinder with said side trusses.

4. A beam type vehicle body having side trusses and deriving its strength principally through said side trusses but having a doorway intersecting a chord of one of said trusses, body reinforcements to transmit the loads from the section of said truss on one side of the doorway to the section thereof on the other side through portions of the body inwardly removed from the side trusses comprising transverse frames interconnecting said side trusses and arranged in greatest 60 65 70 75

- number and closest adjacency in the vicinity of the doorway together with angular section paneling for the exterior of the body constituting short angle section struts by virtue of its angular sections and the close adjacency of said frames.
5. A beam type vehicle body having side trusses and deriving its strength principally through said side trusses but having a doorway intersecting a chord of one of said trusses, body reinforcements to transmit loads from the section of said truss on one side of the doorway to the section thereof on the other side through portions of the body inwardly removed from said side truss comprising longitudinally extending beams located inwardly of the doorway in the under structure of the body, closely spaced transverse frames interconnecting the chords of said trusses at the top and the intersected chord and said inwardly located longitudinal beam at the bottom and corrugated sheathing secured thereto at the bottoms of the corrugations above and below said doorway opening and transverse bulkheads flanking the doorways and secured to and reinforcing the frames at the sides of the doorway.
10. A beam type vehicle body having an underframe and side trusses and deriving its strength principally through said side trusses but having doorways intersecting certain of the chords of said trusses, body reinforcements including transverse diaphragms secured to said side trusses and said underframe inwardly from said side trusses to transmit the loads from sections of the trusses on one side of the respective doorways to the sections on the other side through portions of the body inwardly removed from said side trusses, the doorways leading at their bottoms into step wells and intersecting the lower chords of said trusses, and a longitudinally extending bridging structure between step wells on opposite sides of the body in the form of an inverted channel of the width between the step wells and the full depth of the step wells.
15. A beam type vehicle body having side trusses and deriving its strength principally through said side trusses but having doorways intersecting certain of the chords of the trusses, body reinforcements to transmit the loads from the sections of the trusses on one side of the respective doorways to the sections on the other side through portions of the body inwardly removed from said side trusses, the doorways leading at their bottoms into step wells and intersecting the lower chords of said trusses, and a longitudinally extending bridging structure between step wells on opposite sides of the body in the form of an inverted channel of the width between the step wells and of the full depth of the wells, which channel shaped structure extends longitudinally a considerable distance on each side of the doorways and is comprised of a longitudinally and transversely stiffened web structure at the floor level constituting the bottom wall of the channel and a pair of vertically arranged trusses constituting its side walls.
20. A beam type vehicle body having side trusses, a doorway intersecting a chord of one of said trusses, transverse frames interconnecting the trusses on opposite sides of said doorway, and a webbing extending from truss to truss and longitudinally continuous on either side of said doorway across the transverse plane thereof, which webbing is connected with said transverse frames in a manner to transfer the tension of the intersected chord member
25. across the transverse plane of the door from the section on one side of the doorway to the section on the other side, said webbing having crotched ends constituting it a diagonal cross bracing between the trusses.
30. A beam type trussed housing structure having spaced side trusses and a doorway intersecting a chord of one of said trusses, transverse frames interconnecting the trusses on opposite sides of the doorway, which transverse frames are greatly multiplied in number in the vicinity of the doorway placing them in close proximity, and longitudinally corrugated sheathing affording a stiff and relatively rigid connection between the multiplied frames.
35. A hollow truss type vehicle body, the side frames of which are substantial load carrying truss members each including top and bottom chords and vertical posts interconnecting the chords, a transversely extending floor structure joining said side frames, an arcuate carlines joining the upper chords of said side frames and spaced more closely than the posts of the side frames, a roof sheathing on said carlines of corrugated metal, said roof sheathing in the arcuate portion of the carlines adjacent the side frames, through its connection with the carlines and top chords of the side frames, forming a stiff, compression resisting member having strong resistance against torsion.
40. A hollow truss type vehicle body, the side frames of which are substantial load carrying truss members each including top and bottom chords and posts interconnecting said top and bottom chords, a transversely extending floor structure joining said side frames, and arcuate carlines joining the upper chords of said side frames, a roof sheathing secured to said carlines and chords and comprising longitudinally corrugated sheet metal, said roof sheathing in the arcuate portion of the carlines adjacent the side frames, through its connection with the carlines and the top chords of the side frames, forming a stiff, compression resisting roof member having strong resistance against torsion, lower carlines below the floor structure, joining the bottom chords of the side frames, and longitudinally corrugated sheathing secured to said carlines and the bottom chords of the side frames whereby to additionally strengthen the side frames against torsion.
45. A hollow truss type vehicle body, the side frames of which are substantial load carrying members each including top and bottom chords and vertical posts interconnecting said chords, a transversely extending floor structure joining said side frames, and arcuate carlines joining the upper chords of said side frames, a roof sheathing secured to said carlines and chords and made of longitudinally corrugated sheet metal, said roof sheathing in the arcuate portion of the carlines adjacent the side frames, through its connection with the carlines and top chords of the side frames, forming a stiff, compression resisting roof member having strong resistance against torsion, lower carlines below the floor structure joining the bottom chords of the side frames, longitudinally corrugated sheathing secured to said carlines and to the bottom chords of the side frames, whereby to additionally strengthen the side frames against torsion, and diaphragms secured to portions of the side frames, the floor structure and the upper carlines to additionally resist torsional strains.
50. In a beam type vehicle body having side

- frame trusses and having a doorway intersecting a portion of the lower chord of one of said trusses, and deriving its strength principally through said truss, means to transmit tension stresses across said doorway intersection, means to support said truss in shear to resist vertical loads, and means to resist torsional reactions of portions of the car body on opposite sides of said doorway intersection, said vehicle body having a relatively rigid roof constituting the principal vertical shear support over the doorway and coacting in resisting the principal torsional reaction.
14. In a vehicle body, side trusses which bear the principal load on the vehicle body, a doorway which renders a chord of one of the trusses discontinuous, and a roof structure having a highly developed beam strength to take a large part of the load carried on either flank of the doorway by the truss, and means connecting those portions of the truss flanking the doorway with the roof to transfer load from the truss to the roof and back again, the roof being materially reinforced in the region of the doorway to increase its beam strength in that region quite substantially over that in regions remote from said doorway.
15. In a vehicle body, side trusses which bear the principal load on the vehicle body, a doorway which renders a chord of one of the trusses discontinuous, and a roof structure having a highly developed beam strength materially reinforced longitudinally in the transverse region of the doorway to increase its strength quite substantially over that of remote regions and enable it to take a large part of the load carried on either flank of the doorway by the truss, and means connecting those portions of the truss flanking the doorway with the roof to transfer load from the truss to the roof and back again.
16. A vehicle body comprised of side trusses constituting the principal load carrying frame structure of the vehicle, a doorway intersecting the bottom chord of one truss and rendering the same discontinuous in the plane of the doorway whereby load theretofore carried by it needs be carried by other elements of the vehicle body; a roof structure, a floor, and an underframe structure in the general region of the doorway and extending a considerable distance on each flank of the doorway and each of said structures being materially reinforced in said region to substantially increase its strength over that of regions remote from the doorway whereby they have together the capability of carrying all the load which is carried by the truss on either side of the doorway; and means flanking the transverse region of the doorway connecting the side truss and the floor and the roof in such manner as to transmit the loads from the truss into the floor and roof structures, respectively.
17. A vehicle body in which the side trusses are constituted the principal load carrying framework of the car and having a doorway which intersects and renders discontinuous the lower chord of the truss, together with reinforcing means in the roof and the floor in the longitudinal region of the doorway for materially strengthening said roof and floor in that region over remote regions, whereby to carry all loads which the discontinued truss itself does not carry across the doorway by reason of its discontinuity, which means is provided with extended connections with the portions of the truss on opposite sides of the doorway.
18. A vehicle body in which side trusses are constituted the principal load carrying framework of the car, and having a doorway which intersects and renders discontinuous the lower chord of the truss, together with reinforcing means in the roof and the floor in the longitudinal region of the doorway materially strengthening said roof and floor in that region over remote regions, whereby to carry all the loads which the discontinued truss itself does not carry across the doorway by reason of its discontinuity, which means is provided with extended connections with the portions of the truss on opposite sides of the doorway, the said connections being constituted by the vertically extending reinforcing means connecting with roof paneling and by floor gusset reinforcements connected with the lower chords.
19. A body for a vehicle having in its side wall a certain principal longitudinally extending strength affording element of its framework and adapted to be supported from its opposite ends and provided with a side doorway intermediate its supports intersecting said principal strength element of the framework and rendering the same discontinuous, together with a relatively deep underframe structure and a longitudinally extending strength affording covering therefor and secured thereto and each bridging said doorway.
20. A body for a vehicle having in its side wall a certain principal longitudinally extending strength affording element of its framework and adapted to be supported from its opposite ends and provided with a side doorway intermediate its supports and intersecting said principal strength element of the framework and rendering the same discontinuous, together with a box cross section underframe bridging said doorway.
21. A body for a vehicle having in its side wall a certain principal longitudinally extending strength affording element of its framework and adapted to be supported from its opposite ends and provided with a side doorway intermediate its supports intersecting said principal strength element of the framework and rendering the same discontinuous, together with a floor structure having a reinforcement in the transverse plane of the floor structure bridging the doorway and extending laterally therefrom on each side a distance greater than the width of the doorway itself to effect extended connections with the discontinued frame member, said reinforcements in the transverse plane of the floor structure consisting of an X-shaped plate structure secured longitudinally throughout to the floor structure.
22. A body for a vehicle having in its side wall a certain principal longitudinally extending strength affording element of its framework and adapted to be supported from its opposite ends and provided with a side doorway intermediate its supports intersecting said principal strength element of the framework and rendering the same discontinuous, together with carline frames increased in number in regions close to the doorway over the number in remote regions and carrying the loads from the discontinued framework element inwardly of the doorway into a frame member located inwardly thereof.
23. A body for a vehicle having in its side wall a certain principal longitudinally extending strength affording element of its framework and adapted to be supported from its opposite ends

and provided with a side doorway intermediate its supports intersecting said principal strength element of the framework and rendering the same discontinuous, together with an underframe depending from the car below the discontinued member and through running sheathing cover-

ing said underframe and serving to transmit the loads from said discontinued member into that portion of the underframe which bridges the doorway.
